UNITED STATES PATENT OFFICE.

HENRY J. MARK, OF ST. LOUIS, MISSOURI.

PARTITION-PACKING.

SPECIFICATION forming part of Letters Patent No. 629,041, dated July 18, 1899.

Application filed April 3, 1899. Serial No. 711,564. (No model.)

To all whom it may concern:

Be it known that I, HENRY J. MARK, a citizen of the United States, residing at St. Louis, State of Missouri, have invented certain new and useful Improvements in Partition-Packings, of which the following is a full, clear, and exact description, reference being had to the accompanying drawings, forming a part thereof.

10 My invention has relation to improvements in partition-packings for bottles; and it consists in the novel arrangement and combination of parts more fully set forth in the specification and pointed out in the claims.

15 In the drawings, Figure 1 is a top plan view of a box, showing my partition-packing in the same, the shading of the bottom pad being omitted for the sake of clearness. Fig. 2 is a side elevation of the packing, the adjacent or side wall of the box being removed and a portion of the side liner being also removed. Fig. 3 is a face elevation of one of the longitudinal partitions. Fig. 4 is a face elevation of one of the transverse or intersecting partitions. Fig. 5 is a section, on an enlarged scale, on line 5-5 of Fig. 3. Fig. 6 is a transverse section, enlarged, on line 6-6 of Fig. 3. Fig. 7 is a face elevation of a modification of the longitudinal partition. Fig. 8 is a face elevation of a modification of the transverse partition. Fig. 9 is a top edge view of Fig. 7, and Fig. 10 is a top edge view of Fig. 8.

30 The object of my present invention is to construct a partition-packing which shall insure a maximum amount of cushioning to the walls of the bottles confined within the several compartments of the packing, one which will possess a maximum degree of elasticity, one in which the partitions separating the several compartments of the packing possess an inherent stiffness sufficient to preserve the several bottles against violent impact against one another, one in which the walls of the compartments will yield sufficiently to allow for variable diameters or sizes of bottles, and one possessing further and other advantages more apparent from a detailed description of the invention, which is as follows.

50 Referring to the drawings, 11 represent a series of vertically-arranged parallel paste-

board foundation strips or sheets covered on each face by a sheet of corrugated wood veneer 2 of the same width, the corrugations running across the width of the sheet at an angle preferably inclined to the edges of the strip, the veneer strips being sewed to the pasteboard center strip by stitches 3 running lengthwise and approximately along the medial longitudinal line of the composite wall or partition 55 thus formed. Each partition is recessed to the middle of the depth or width thereof, the recesses 4 being disposed along one edge and at right angles thereto and extending to a point adjacent to the line of stitches referred to. 60 The partitions, as above described, are crossed or intersected by a second series of similar parallel partitions formed in a similar way by pasteboard center strips 1' 1', covered on each face by corrugated-wood-veneer strips 2' 2', 70 secured by stitches 3', the recesses 4' of the intersecting series tending downward, while the recesses 4 of the first series tend upward, the two series crossing each other at the recesses, the recess of one wall spanning the 75 faces of the intersecting wall to the full depth of the recess, whereby when the several partitions are assembled their upper and lower edges will lie in respectively parallel planes, the contiguous edges lying in the same plane. 80 By the formation of the recesses 4 4' as indicated there is formed between any two consecutive recesses a tongue or section which is more or less yielding from a line connecting the bases of the two recesses to the free edge 85 of such section; but as four of such sections enter into the formation of the four walls constituting any compartment 5 made by the intersection of any four partitions it follows that the walls of such compartment will readily yield in accommodating bottles which may vary more or less in the diameters of their body portions. The assembled series of partitions intersecting each other as specified 90 rest upon a bottom cushioning-pad comprising a center sheet of pasteboard 6 and upper and lower corrugated veneer sheets 7 7, the pad resting on the bottom of the box 8 in which the packing is confined. The side and end compartments 5 are completed as to their 95 outer wall by the side and end liners or pads, each composed of a center sheet of pasteboard 100

9, covered by corrugated-wood-veneer sheets 10 10, attached thereto by sewing, as clearly obvious from Fig. 2.

In all the foregoing cases the veneer sheets 5 are preferably corrugated in the act of cutting or stripping the same from the original block of wood, though I am not limited to this specific form of veneer. Neither do I wish to be understood as limiting myself to 10 a pasteboard center, for any other soft and pliable center sheet or filling of other material falls within the spirit of my invention. Neither do I limit myself to wood veneer; but any other veneer having yielding and elastic 15 qualities may be substituted for wood—such, for example, corrugated paper, papier-mâché, tule-grass, and the like.

In the form thus far described the center strip of the partition-walls extends the full 20 depth or width of the strip, and the veneer covering is disposed along both faces of the strip; but for packing light ware or light bottles I may substitute a pasteboard strip 11 of but one-half the full width or depth of the 25 completed partition, the veneer covering 12 being disposed on only one face thereof and the recesses 13 extending to the edge of the pasteboard. This modification is illustrated in Figs. 7 to 10, inclusive.

30 While I prefer that the corrugations of the several strips comprising the walls of the compartments in which the bottles are inserted shall run at an angle to a line perpendicular to the upper and lower edges of any strip, I 35 do not wish to limit the invention thereto, as the corrugations themselves may run at right angles to said opposite edges. While I have referred to the veneer sheets as being stitched to the center plane pasteboard strip, they 40 may be secured thereto in any other equivalent manner.

Having described my invention, what I claim is—

1. In a partition-packing, a composite wall 45 or partition comprising a center plane foundation-strip, a sheet of veneer secured thereto and covering either face of the foundation-strip, the veneer being corrugated and the corrugations running in parallel rows from 50 the lower to the upper edge of the sheet, the partition having a series of recesses formed adjacent to one edge thereof and extending in parallel series to approximately the middle of the depth of the partition, substantially 55 as set forth.

2. In a partition-packing, a composite wall or partition comprising a center plane foundation-strip, a sheet of veneer secured thereto by stitching and covering each face of the 60 foundation-strip, the veneer being corrugated,

and the corrugations running in parallel rows from the lower to the upper edge of the sheet, the partition having a series of recesses formed adjacent to one edge thereof and extending in parallel series to approximately 65 the middle of the depth of the partition and to a point adjacent to the line of stitching by which the veneer is secured to the foundation-strip, substantially as set forth.

3. In a partition-packing, a composite wall 70 or partition, comprising a center plane foundation-strip of pasteboard, a sheet of wood veneer secured by stitching and covering each face of the foundation-strip, the veneer being corrugated and the corrugations running in parallel rows from the lower to the upper edge of the sheet, the partition having a series of recesses formed adjacent to one edge thereof and extending in parallel series to approximately 75 the middle of the depth of the partition and to a point adjacent to the line of stitching by which the veneer is secured to the foundation-sheet, substantially as set forth.

4. A partition-packing comprising a series 80 of parallel composite walls or partitions, each composed of a plane foundation-sheet, having secured thereto by stitching a corrugated wooden veneer sheet along each face thereof, the partition having a series of recesses extending from one of its longitudinal edges to the middle of the width thereof, and to a point adjacent to the line of stitching, said series being intersected by a second parallel row of 85 similar partitions, the recesses of one being 90 opposite those of the other, and embracing the faces of the intersecting wall to the full depth of the recess whereby the opposite edges of the several partitions are disposed along 95 parallel planes, the packing being provided 100 with a suitable bottom pad, and side and end layers, substantially as set forth.

5. In a partition-packing, a composite wall or partition comprising a center plane foundation-strip of pasteboard, a sheet of wood 10 veneer disposed adjacent thereto and covering each face thereof, the veneer being corrugated and the corrugations running in parallel rows from the lower to the upper edge of the sheet, the partition having a series of 11 recesses formed adjacent to one edge thereof and extending in parallel series to approximately the middle of the depth of the partition, substantially as set forth.

In testimony whereof I affix my signature in presence of two witnesses.

HENRY J. MARK.
